Delaware

Application June 18, 1937, Serial No. 148,893

12 Claims. (Cl. 179—171)

This invention relates to modulated-carrier signal receivers and, more particularly, to signal-selecting systems of such receivers and methods of, and means for, controlling the fidelity and 5 selectivity of reproduction thereof to discriminate against undesired signals.

It is frequently difficult in receivers of the type described to reproduce a desired signal without undesired signal interference such as 10 is caused by signals on carrier frequencies near the desired signal carrier and by static and other so-called background noises which are ordinarily present at the higher modulation frequencies. In order, therefore, to obtain faithful reproduction 15 of the desired signal, substantially free from undesired signal interference, it is necessary to utilize selective systems which are effective to pass a band of desired signal frequencies sufficiently narrow to attenuate greatly the undesired relatively high-frequency signal interference.

Heretofore various selective systems have been devised for this purpose, adaptable for use in either the radio-frequency or audio-frequency 25 channel of the receiver. Certain of such selective systems have included means for automatically adjusting the width of the selected band of frequencies so as to contract the band only in the presence of undesired signals of sufficient 30 amplitude to cause appreciable interference or noise. In the absence of interference, the width of the selected band is expanded sufficiently to admit and pass all of the useful signal frequencies, thus procuring the highest fidelity of 35 production.

While such systems as those heretofore used have proved generally satisfactory, they have, however, been subject to certain disadvantages. For example, the frequency bands which they 40 have been capable of passing have been relatively narrow with respect to their mean frequency and a critical cutoff has been extremely difficult to obtain. Where a selector system is used in an audio-frequency channel, both of these considerations are important since it is necessary to 45 pass a relatively very wide band of frequencies and it is essential that frequencies higher than those of the desired band be greatly attenuated.

It is an object of the present invention to provide 50 an improved signal-selector system for passing a band of frequencies with substantially uniform gain for all frequencies within the band and with substantial attenuation of frequencies higher than the highest frequency of the band.

It is a further object of the invention to provide

an improved signal-selector system adjustable to vary the width of the band of frequencies passed thereby without substantially altering the gain of the system.

In accordance with a preferred embodiment 5 of the invention, there is provided a signal-selector system for passing a band of frequencies comprising aperiodic frequency-discriminating terminal circuits. Separate directive coupling means are provided for individually coupling the 10 circuits in the forward and backward directions. The coupling means are substantially less frequency-discriminative than the terminal circuits and co-operate with these circuits to provide a coupling reaction therebetween which is de- 15 generative over the main portion of the band and regenerative at the higher and lower frequencies of the band and which is also preferably degenerative at frequencies higher than the highest frequency of the band. Means are also pro- 20 vided for simultaneously so adjusting the coupling means relative to each other as to adjust the width of the band of frequencies passed by the system without substantially altering the gain of the system.

For a better understanding of the invention, together with other and further objects thereof, reference is had to the following description taken in connection with the accompanying drawing, and its scope will be pointed out in the appended 25 claims.

In the accompanying drawing, Fig. 1 is a schematic diagram of a complete modulated-carrier signal receiver embodying one form of the present invention, while Fig. 2 is a group of curves illustrating certain operating characteristics of the 30 system shown in Fig. 1 to aid in the understanding of the invention.

Referring now more particularly to Fig. 1, there is shown schematically a superheterodyne 40 receiver embodying a radio-frequency amplifier 10 having its input circuit connected with an antenna 11 and ground 12. Connected in cascade to the output circuit of the amplifier 10, in the order named are an oscillator-modulator or frequency changer 13, an intermediate-frequency amplifier and band-pass selector system 14, a detector and automatic amplification control or A. V. C. rectifier 15, an audio-frequency amplifier and selector system 16, additional stages of 45 audio-frequency amplification 17, and a loud-speaker 18. Suitable connections 19 and 19' are provided for supplying an A. V. C. potential negatively and positively, respectively, to the control 50 grids of one or more of the tubes of the preceding 55

- stages of the system. The stages 10-15, inclusive, and 17 may be of any suitable conventional construction and are shown in schematic form for the purpose of brevity. The output circuit of the detector 15 may include a conventional direct current blocking condenser 20 and voltage divider resistance 21, by adjustment of which the volume level output of the receiver may be controlled in the usual manner.
- 10 Preferably, the amplifier and selector 14 includes an adjustable band-pass selector of a suitable design for automatically controlling the width of the band of frequencies passed thereby in accordance with received signal conditions in 15 order to reduce undesired signal disturbances at relatively high modulation frequencies. This control is preferably effected by the application of a unidirectional control-bias voltage to control electrodes of the tubes of this system. In order 20 to develop a suitable biasing voltage for this purpose, as well as for controlling the audio-frequency amplifier and selector system 16, as will be hereinafter explained, there is connected to the output circuit of the intermediate-frequency 25 amplifier 14 a frequency detector 22 having a rectifier 23 coupled to its output circuit. Part of the output voltage of rectifier 23 is applied, by way of a lead 24 including a filter resistor 25, to a terminal of the amplifier and selector system 14.
- 30 The details of the selector system 14, as well as the detector 22 and rectifier 23, constitute no part of the present invention and, therefore, are not described herein. For a detailed description of the construction and operation of suitable apparatus for these stages, reference is had to applicant's copending application, Serial No. 148,894, filed concurrently herewith, for improvements in Automatic selectivity and fidelity control. The system of the present invention, also described and illustrated in that copending application but not claimed therein, is embodied in the audio-frequency amplifier and selector system 16 and will be hereinafter described in detail.
- 35 Neglecting for the moment the novel features of the amplifier and selector system 16, the system as thus far described includes the features of a superheterodyne receiver with automatic selectivity control. Since the operation of such a receiver is well understood in the art, a detailed explanation thereof is considered unnecessary.
- 40 Briefly, however, signals intercepted by the antenna 11 are selected and amplified by the radio-frequency amplifier 10 and converted into intermediate-frequency signals in a conventional manner in the oscillator-modulator 13. The intermediate-frequency signals are thereupon selected and amplified by the amplifier and selector system 14 and translated to the detector and A. V. C. rectifier 15, wherein the audio-frequency signal and unidirectional A. V. C. voltages are derived.
- 45 The audio-frequency signal is further selected and amplified by the audio-frequency stages 16 and 17 and translated therefrom to the loud-speaker 18 for reproduction. The unidirectional voltages developed by the A. V. C. rectifier are applied negatively and positively to control electrodes of tubes in the preceding stages of the system, thereby to maintain the signal output amplitude of the intermediate-frequency amplifier and 50 selector system 14 within a relatively narrow range for a wide range of signal input amplitudes. While the detector 15 detects only amplitude modulation of the received carrier, the desired signal being represented by such modulation, undesired signal disturbances cause both

amplitude and frequency modulation of the carrier and the detector 22 detects only the modulation of the latter type. This detected frequency modulation is rectified by the rectifier 23 to provide a unidirectional control-bias voltage which varies in accordance with the undesired signal disturbances. The amplifier and selector system 14 is controlled by the unidirectional bias voltage developed by the rectifier 23 so as to decrease the width of the band of frequencies passed by the system in response to received undesired signal disturbances, thereby to reduce the effects of such disturbances.

Referring now more particularly to the parts of the receiver embodying the present invention, the audio-frequency amplifier and selector system 16 comprises frequency-discriminating input and output terminal circuits which are substantially aperiodic within the pass band of the selector. The aperiodic input circuit is connected across the output section of voltage divider 21 and includes, in series, a resistor 28, a condenser 30, a resistor 31, and an audio-frequency by-pass condenser 44, and a condenser 29 is connected in parallel with the elements 30, 31, and 44. The output circuit includes a primary winding 32 of an audio-frequency transformer 33, the secondary winding 34 of which is coupled to the additional audio-frequency amplifier stages 17. A trap circuit comprising an inductor 35 and a condenser 36, in series, is connected across the winding 32. The trap circuit 35, 36 is tuned to 10 kilocycles, the usual frequency difference between carriers on adjacent channels, so that it leaves the output circuit also aperiodic at the lower frequencies, within the band passed by the system.

Coupling the terminal circuits, just described, in the forward direction is a vacuum tube having its input circuit coupled across resistor 31 and its output circuit coupled across the winding 32. Coupling the terminal circuits in the backward direction is a vacuum tube 27 having its input circuit coupled across a portion of winding 32 through the grid condenser 37 and its output circuit coupled to the input circuit of the system by way of a resistor 38 in its cathode lead, the audio-frequency voltage across which is coupled to the input circuit of the tube 26 through a high resistor 39, across condenser 29 and in series with condenser 30. The directive coupling means comprising the tubes 26 and 27 and their couplings to the terminal circuits are substantially nondiscriminative and, therefore, are less frequency-discriminative than the terminal circuits. Operating potentials are supplied to the electrodes of the tubes 26 and 27 from suitable sources, as indicated by the batteries 40.

For the purpose of controlling the selector and amplifier system 16 in accordance with the presence of undesired signal interference, unidirectional voltage developed by the rectifier 23 is applied negatively to the control grids of the tubes 26 and 27 by way of connections 41 and 42, respectively, the connection 41 including a suitable filter comprising a series resistor 43 and a shunt condenser 44 and the connection 42 including a filter comprising a series resistor 45 and a shunt condenser 46, connected to grid leak 47.

Referring now to the operation of the audio-frequency amplifier and selector 16, over the major part of the audio-frequency range a degenerative feedback is provided. This relationship is obtained by means of the phase reversal of the signal which is effected by the forward

coupling tube 26. Due to the manner in which the backward coupling tube 27 is coupled to the input circuit, no phase reversal of the feed-back voltages is effected thereby. The impedance elements in the input and output circuits are so proportioned and related that they produce no substantial resultant phase shift of the signal voltages of frequencies within the major middle portion of the frequency range which the system 5 is designed to pass. Therefore, the resultant feed-back voltage is reversed in phase with respect to the input voltage at such frequencies.

At the lower frequencies of the audio-frequency range a regenerative feedback is effected. This 10 is due primarily to the transformer primary winding 32, the voltage across which leads the anode current of tube 26 by approximately 90 degrees, and to the series condenser 30 which at the lower frequencies has an impedance comparable with that of resistors 31 and 39 combined and draws a leading current which develops across resistor 31 a feed-back voltage having a leading phase angle approaching 90 degrees with respect to the feed-back voltage across resistor 38. Thus, these two 90 degree leading 15 phase displacements, together with the 180 degree phase shift effected by the forward coupling tube, results in a feed-back voltage tending to be in phase with the input voltage applied to the grid of tube 26 so that the system is regenerative at the lower frequencies.

Also, at the higher frequencies of the audio band and below the resonant frequency of the trap circuit, a regenerative feedback is effected. 20 This is due primarily to the trap circuit 35, 36 and the parallel condenser 29. At these higher frequencies below the trap frequency, the load impedance of the tube 26 is determined primarily by the trap circuit 35, 36 which is capacitive 25 at frequencies lower than the resonant frequency of the trap, so that the voltage thereacross lags the anode current of tube 26 by a phase angle approaching 90 degrees. A portion of this voltage, derived from the winding 32, is applied to 30 the grid of the backward coupling tube 27. Also, at these higher frequencies, the reactance of condenser 29 is comparable with that of resistors 28 and 21, in series, or that of condenser 30 and resistor 31, in series, so that a substantial part 35 of the current due to the voltage derived from resistor 38 flows through condenser 29. However, resistor 39 maintains this current nearly in phase with the voltage across resistor 38, so that the feed-back voltage across condenser 29 lags 40 so that across resistor 38 by an angle approaching 90 degrees. Thus, the resultant feed-back signal 45 undergoes a phase reversal in tube 26 and two additional shifts approaching 90 degrees, lagging so that it tends to be in phase with the input 50 voltage, and the system is regenerative.

Frequencies higher than the trap frequency are, for practical purposes, outside of the useful range of audio frequencies and it is, therefore, desirable that voltages at these frequencies 55 be attenuated. The trap circuit is inductively reactive at these frequencies and, therefore, shifts the feed-back voltage by an angle approaching 90 degrees leading, rather than lagging as at frequencies just below the trap frequency. 60 Hence, resultant phase displacement is only the 180 degree phase displacement effected by the forward coupling tube 26 and the feedback is degenerative at the frequencies above the trap frequency, thereby effecting the desired attenuating 65 action.

In brief, therefore, the forward and backward coupling means are substantially less discriminative than the terminal circuits of the system and co-operate with these terminal circuits to provide a coupling action therebetween which is 70 degenerative over the major portion of the band passed by the system and at frequencies higher than the highest frequency of this band, and is regenerative at the higher and lower frequencies of the band. The system, therefore, when 75 properly adjusted, passes the frequencies of the desired band with substantially uniform gain while greatly attenuating undesired frequencies higher than the highest frequency of the band.

The adjustment of the selectivity of the amplifier and selector system 16 may best be explained with reference to the curves shown in Fig. 2 which illustrate the operating characteristics of this system and in which the abscissae represent frequencies in cycles, and the ordinates indicate relative gain of the system in voltage ratio. Curve A represents the normal condition of operation, or maximum fidelity of reproduction, which is obtained with maximum feedback, while curve B represents the condition of minimum fidelity of reproduction which is obtained with minimum feedback.

Considering then an initial condition where the negative-biasing potential developed by the rectifier 23 in response to undesired signal disturbances and applied to the control grid of the tube 27 is sufficient to reduce the transconductance of the tube to zero, curve B represents the frequency-gain characteristic of the system. This curve is relatively narrow and includes a sharp dip to 35 zero at 10 kilocycles, representing infinite attenuation at the resonant frequency of the trap circuit. Curve B indicates that the system not only is relatively sharply selective, so as to reduce the signal disturbances at the higher frequencies below the resonant trap frequency, but also attenuates the frequencies higher than the highest frequency of the band.

The transition from the condition represented by curve B to that represented by curve A results 45 partly from the adjustment of the feed-back effect and partly from adjustment of the relative transconductances of the forward and backward coupling tubes 26 and 27; that is, while the feed-back obtained is dependent only on the product of 50 the forward and backward transconductances, the gain of the system is dependent not only on this product, but also on the ratio of these two transconductances. If then, under the conditions assumed above, feedback were effected merely by 55 increasing the transconductance of the backward coupling tube 27, the effect would be to lower the frequency-gain characteristic in the middle of the range, and also above 10 kilocycles, and to raise the curve slightly at the lower frequencies and 60 the higher frequencies below 10 kilocycles. Curve C represents the condition which would then be obtained.

In accordance with the present invention, however, the width of the band is adjusted by decreasing the negative bias on both the forward and backward tubes simultaneously and in such proportion relative to each other that the resultant increase in forward transconductance holds the gain uniform in the middle of the range in 70 spite of the degenerative feedback caused by increasing the backward and incidentally the forward transconductances. Increasing both the forward and backward transconductances at the same rate would result in a slight increase in gain. 75

- Hence, the forward transconductance is preferably increased at a slightly lower rate. While there may be exceptions to this rule, when a wide range of feed-back effect is required, no difficulty is likely to be experienced in determining, for any case, what relative variations of the negative-bias voltages are required for the two tubes. It is to be noted that the manner in which the feedback is made degenerative, not only in the middle of the band but also above 10 kilocycles, is relatively simple; that is, the use of the trap circuit in the output circuit of the system provides the desired effect. Condenser 29 and trap circuit 35, 36 may be interchanged if desired. If trap circuits, however, were connected both in the input and in the output circuits, the advantage would be lost since the feedback would then be regenerative at frequencies above, as well as just below, the trap frequency.
- 20 While there has been described what is at present considered the preferred embodiment of this invention, it will be obvious to those skilled in the art that various changes and modifications may be made therein without departing from this invention, and, therefore, it is aimed in the appended claims to cover all such changes and modifications as fall within the true spirit and scope of this invention.

What is claimed is:

- 30 1. A selector system for passing a band of frequencies comprising frequency-discriminating terminal circuits substantially aperiodic within the pass band of the selector, directive coupling means coupling said circuits in one direction, separate directive coupling means coupling said circuits in the other direction, said coupling means being substantially less frequency-discriminative than said terminal circuits and co-operating with said terminal circuits to provide a coupling reaction therebetween which is degenerative over the major portion of said band and is regenerative at the higher and lower frequencies of said band, and means for simultaneously so adjusting said coupling means relative to each other as to adjust the width of the band of frequencies passed by said system without substantially altering the gain of the system.
2. A selector system for passing a band of frequencies comprising frequency-discriminating terminal circuits substantially aperiodic within the pass band of the selector, directive coupling means coupling said circuits in one direction and separate directive coupling means coupling said circuits in the other direction, said coupling means being substantially less frequency-discriminative than said terminal circuits and co-operating with said terminal circuits to provide a coupling reaction therebetween which is degenerative over the major portion of said band, is regenerative at the higher and lower frequencies of said band, and is degenerative at frequencies higher than the highest frequency of said band.
3. A selector system for passing a band of frequencies comprising frequency-discriminating terminal circuits substantially aperiodic within the pass band of the selector, directive coupling means coupling said circuits in one direction and separate directive coupling means coupling said circuits in the other direction, said coupling means being substantially less frequency-discriminative than said terminal circuits and co-operating with said terminal circuits to provide a coupling reaction therebetween which is degenerative over the major portion of said band, is regenerative at the higher and lower frequencies of said

band, and is degenerative at frequencies beyond one of the limiting frequencies of said band.

4. A selector system for passing a band of frequencies comprising frequency-discriminating terminal circuits substantially aperiodic within the pass band of the selector, directive coupling means coupling said circuits in one direction and separate directive coupling means coupling said circuits in the other direction, said coupling means being substantially less frequency-discriminative than said terminal circuits and co-operating with said terminal circuits to provide a coupling reaction therebetween which is degenerative over the major portion of said band, is regenerative at the higher and lower frequencies of said band, and is degenerative at frequencies higher than the highest frequency of said band, and means for simultaneously so adjusting said coupling means relative to each other as to adjust the width of the band of frequencies passed by said system without substantially altering the gain of the system.

5. A selector system for passing a band of frequencies comprising frequency-discriminating terminal circuits substantially aperiodic within the pass band of the selector, one of said circuits comprising resistance and reactance elements, directive coupling means for coupling said terminal circuits in one direction and separate directive coupling means coupling said terminal circuits in the other direction, said elements of said terminal circuits being of such types and values that they co-operate with said coupling means to provide a coupling between said terminal circuits which is degenerative over the major portion of said band and at higher frequencies than the highest frequency of said band and is regenerative at the lower and higher frequencies of said band.

6. A selector system for passing a band of frequencies comprising frequency-discriminating terminal circuits substantially aperiodic within the pass band of the selector including resistance and reactance elements, coupling means for coupling said terminal circuits in one direction and separate coupling means coupling said terminal circuits in the other direction, said elements of said terminal circuits being of such types and values that they cooperate with said coupling means to provide a coupling between said terminal circuits which is degenerative over the major portion of said band and at higher frequencies than the highest frequency of said band and is regenerative at the lower and higher frequencies of said band, and means for adjusting said coupling means to adjust the band-pass characteristic of said system.

7. A selector system for passing a band of frequencies comprising an aperiodic input circuit including a resistance-reactance network, an aperiodic output circuit including an impedance network effective to develop voltages displaced in phase with respect to the output current at higher and lower frequencies of said band, forward coupling means coupling said circuits and effective to reverse the phase of the output current with respect to the input voltage at frequencies passed thereby, separate backward coupling means coupling said output circuit to said resistance-reactance network, said resistance-reactance network being effective to develop therein a voltage displaced in phase with respect to the voltage derived from said output circuit at said higher and lower frequencies and said coupling means being substantially nonfrequency-discriminative, and means for adjusting said coupling means to adjust the width of the band of frequencies passed

thereby without substantially altering the gain of the system.

8. A selector system for passing a band of frequencies comprising frequency-discriminating terminal circuits substantially aperiodic within the pass band of the selector, directive coupling means coupling said circuits in one direction and effective to cause a phase reversal of the signal passed by said system and separate directive coupling means coupling said circuits in the other direction, said coupling means being substantially less frequency-discriminative than said terminal circuits, a pair of phase-shifting means each effective to displace the phase of the signal by an angle approaching 90 degrees leading at the lower frequencies of said band, and a second pair of phase-shifting means each effective to displace the phase of the signal by an angle approaching 90 degrees lagging at the higher frequencies of said band, whereby the coupling between said terminal circuits is degenerative over the major portion of said band and is regenerative at the higher and lower frequencies of said band.

9. A selector system for passing a band of frequencies comprising frequency-discriminating terminal circuits substantially aperiodic within the pass band of the selector, directive coupling means coupling said circuits in one direction and effective to cause a phase reversal of the signal passed by said system and separate directive coupling means coupling said circuits in the other direction, said coupling means being substantially less frequency-discriminative than said terminal circuits, a pair of phase-shifting means each effective to displace the phase of the signal by an angle approaching 90 degrees leading at the lower frequencies of said band, and a pair of phase-shifting means each effective to displace the phase of the signal by an angle approaching 90 degrees lagging at the higher frequencies of said band, one of said last-mentioned means being a trap circuit also effective to displace the phase of the signal by an angle approaching 90 degrees at frequencies beyond one of the limiting frequencies of said band and in a direction opposite to that of the other of said last-mentioned means, whereby the coupling between said terminal circuits is degenerative over the major portion of said band and at said frequencies beyond one of the limiting frequencies of said band and is regenerative at the higher and lower frequencies of said band.

10. A selector system for passing a band of frequencies comprising an input circuit including a resistance-reactance network, an output circuit comprising an impedance network including a resonant trap circuit and effective to develop voltages displaced in phase with respect to the output current, in one sense at lower frequencies of said band and at frequencies higher than the highest frequency of said band, and in an opposite sense at higher frequencies of said band, forward coupling means coupling said circuits and effective to reverse the phase of the output current with respect to the input voltage at frequencies passed thereby, and separate backward

coupling means coupling said circuits, said resistance-reactance network being effective to develop therein voltages displaced in phase with respect to the voltage derived from said output circuit in one sense at said lower frequencies of said band and in an opposite sense at said higher frequencies of said band and at frequencies higher than the highest frequency of said band, said two coupling means being substantially nonfrequency-discriminative.

11. A selector system for passing a band of frequencies comprising an input circuit including a resistance-reactance network, an output circuit comprising an impedance network including a resonant trap circuit and effective to develop voltages displaced in phase with respect to the output current, in one sense at lower frequencies of said band and at frequencies higher than the highest frequency of said band, and in an opposite sense at higher frequencies of said band, forward coupling means coupling said circuits and effective to reverse the phase of the output current with respect to the input voltage at frequencies passed thereby and separate backward coupling means coupling said circuits, said resistance-reactance network being effective to develop therein voltages displaced in phase with respect to the voltage derived from said output circuit in one sense at said lower frequencies of said band and in an opposite sense at said higher frequencies of said band and at frequencies higher than the highest frequency of said band, said two coupling means being substantially nonfrequency-discriminative, and means for adjusting said coupling means to adjust the width of the band of frequencies passed thereby without substantially altering the gain of the system.

12. A selector system for passing a band of frequencies comprising an input circuit including a resistance-reactance network, an output circuit comprising an impedance network including a trap circuit sharply responsive at the highest frequency of said band and being effective to develop voltages displaced in phase with respect to the output current in a leading direction at lower frequencies of said band and at frequencies higher than the highest frequency of said band, and in a lagging direction at higher frequencies of said band, forward coupling means coupling said circuits and effective to reverse the phase of the output current with respect to the input voltages at frequencies passed thereby, and separate backward coupling means coupling said circuits, said resistance-reactance network being effective to develop therein voltages displaced in phase, with respect to the voltages developed by said output circuit, in the same sense as the phase displacements effected by said output circuit at said higher and lower frequencies of said band and in an opposite sense to the phase displacement effected by said output circuit at said frequencies higher than the highest frequency of said band, said coupling means being substantially non-frequency-discriminative.
